RAILWAY RAIL JOINT

Rene A. Fiechter, Douglaston, N.Y., assignor, by mesne assignments, to American Railroad Curvelining Corporation, a corporation of New York

Filed May 27, 1957, Ser. No. 661,921
11 Claims. (Cl. 238—151)

This invention relates to a railway rail joint, referring particularly to such a joint in which the rail ends are integrally but non-homogeneously connected in such a manner that the rails are securely held against longitudinal movement relative to each other.

An object of the invention is to provide a rail joint which cannot accidentally work itself loose or become accidentally loosened under any conditions whatever, apart from the application of some violent force.

In a track in which the rails are separably joined together by splice bars in a rigid or "frozen" manner, there is comparatively little pounding and wear on the rail ends, where pounding and maximum wear usually occurs, and this is more especially true the closer together the rail ends are disposed.

As compared with a track in which the rails are welded together at their ends, it is advantageous especially from the standpoint of permitting quick and easy removal and replacement of individual rails, to separably connect the rails by means of splice bars. Accordingly, the present invention has more particularly in view to provide, on the one hand, a track wherein the rails are separably connected for individual removal and replacement, and wherein the rails are rigidly connected in abutting or relatively closed end to end relationship against the possibility of endwise movement relative to each other; and, on the other hand, to provide joints embodying novel features of construction for separably connecting the rails and effectively holding them rigidly aligned and against relative longitudinal movement.

With the foregoing and other purposes in view, the rail joint (or the like) includes the provision of a synthetic resin bonding agent interposed between two metallic parts (e.g., the rails and the fish plates, if any) which resin can be, and is, molecularly engaged with the surfaces to be connected so strongly as to obtain the desired results. A similar bonding agent may also be provided between a metallic part and a part composed of some other material (e.g., the tie plates and the ties).

A practical embodiment of the invention is represented in the accompanying drawings wherein:

FIG. 1 represents a side elevation of a rail joint together with an adjacent tie and tie plate on which the rail is secured,

FIG. 2 represents a transverse vertical section on the line II—II of FIG. 1, on an enlarged scale, and

FIGS. 3, 4 and 5 represent, in somewhat diagrammatic cross-section, modifications in which no fish plates are used, the bonding agent being retained in effective position by the use of a two piece (FIG. 3), one piece (FIG. 4) or three piece (FIG. 5) metal sleeve.

Referring to the drawings, a rail joint is shown as comprising the adjacent ends of two steel rails, 2, a pair of fish plates 3, 4 (also sometimes known as side plates, splice plates or joint bars) and bolts 5. The rails are intended to be supported in the customary manner upon wooden ties 6 to which they are secured by means of spikes 7, with or without the interposition of tie plates 8.

In order to effect the bonding of rail ends according to the present invention, it is desirable to clean and roughen the metal surfaces to be bonded (as by sand-blasting), to apply to one or both of said surfaces a coating of an epoxy resin (ethoxyline class) in a semi-liquid

2

state, to assemble, or reassemble, the parts in their desired relation including normal pressures, tensions and the like, and to cure the resin by the application of heat for a suitable period of time.

5 A film of such a bonding agent is represented in the drawings (the thickness being exaggerated) at 9 and 10, between the fish plates 3, 4 and the contiguous parts of the rails, at 11 in the clearance between the shank of the bolt 5 and the holes through which it passes, and at 12 between the abutting ends of the rails. In actual practice it is preferred to have the metal parts as close together as possible, i.e., practically "capillary closeness"—about 0.1 mm. If this result cannot be achieved with respect to the rail-end bond at 12, the space can be filled with one or more resin coated shims of appropriate shape and thickness, including a wedge-shaped one to ensure tight filling of the gap.

10 The bonding material presently preferred is the ethoxyline resin known as "Araldite" Type I (the Ciba brand of a reaction product of epichlorohydrin and p,p'-isopropylidene bisphenol). This material is solid at room temperature, begins to soften at 50°—60° C. (122°—140° F.) and flows freely at 130°—140° C. (266°—284° F.). For convenience in handling and applying this material it is 15 preferably formulated with a suitable polymer so as to be semi-liquid at the temperature of application. It contains terminal epoxy groups and is soluble in the usual ketone solvents.

20 When heated for some time at temperatures above 120° C. (248° F.) curing begins and the resin adheres firmly to the surface with which it is in contact; no volatile substances are given off and the volume undergoes practically no change. The surface of the work piece must be thoroughly cleaned and may (but need not) be roughened. 25 The resin may be applied in rod or powder form to clean metal surfaces which have been heated to 130°—150° C. (266°—302° F.); or preferably in semi-liquid form to unheated surfaces, and when the resin has stuck to the surfaces as a fairly uniform film the parts are brought together 30 and held firmly until the curing has been completed. The resin described above can be cured over a wide range of temperatures in inverse relation to the curing time, as shown in the table below. At temperatures of 190° C. (374° F.) and below, it is practically impossible to 35 destroy the bonding agent by exceeding the recommended (minimum) time, but at temperatures of 200° C. (392° F.) and above, the maximum time limits must be carefully observed.

	Curing temp. at joint	Minimum time	Maximum time
110° C.—230° F.	48 hrs.	No limit.	
120° C.—248° F.	24 hrs.	Do.	
130° C.—266° F.	10 hrs.	Do.	
140° C.—284° F.	5 hrs.	Do.	
150° C.—302° F.	3 hrs.	Do.	
160° C.—320° F.	2 hrs.	Do.	
170° C.—338° F.	30 min.	Do.	
180° C.—356° F.	55 min.	Do.	
190° C.—374° F.	45 min.	Do.	
200° C.—392° F.	30 min.	24 hrs.	
220° C.—428° F.	10 min.	60 min.	
250° C.—482° F.	7 min.	10 min.	
280° C.—536° F.	3 min.	5 min.	

65 In actual practice the heating of the joint can be effected in various ways, as by means of a portable gas or electric heater designed to apply heat locally to the area in which the joint is being formed, whether it be a rail-end joint or a tie plate anchoring connection. The heat and time selected will depend on various factors, 70 but a relatively quick cure is obviously desirable in locations where the track being worked on cannot be kept out of service for a long period of time, while a slower

cure (for a few hours) at lower temperatures may be used whenever possible.

As an example of the holding power of a bonding agent such as that described above, it has been found that the bonding of the ends of 132 lb. rails, using 6-hole fish plates, exhibits a shear strength of over 400,000 lbs.

In addition to the rigid attachment of adjacent rail ends to the fish plates and to each other, it is frequently very important to fix the tie plates 8 immovably on their respective ties 6. For this purpose a bonding agent of the same type can be used, as shown at 13, with the proviso that the body of resin here may be substantially thicker and may even constitute a sort of pad uniting the tie plate to the tie very firmly but with a measurable amount of resiliency. Such a resin pad may, for the sake of economy and/or resiliency contain a suitable organic or inorganic filler (such as ground cork).

While epoxy type resins have recently been used for metal bonding in certain other industries, the possibility of using such bonding agents under the extremely heavy duty requirements of railroad track joints has not previously been suggested and the success of this development is of very great importance.

The strength of the adhesive bond is such that, in some instances, the fish plates can be entirely dispensed with and replaced by relatively thin metal sleeves encasing the rail ends (except for the head) and bonded thereto as described above. In FIG. 3 the sleeve is shown as comprising two unequal parts 14 and 15, the part 14 fitting closely against one side of the rail and the part 15 fitting and covering the other side and the bottom, the parts having matching flanges 14' and 15' where they are preferably bonded to each other.

The one piece sleeve 16 of FIG. 4 can most conveniently be applied where the adjacent rail ends are so located that the sleeve can be slid all the way onto one end while the other end is brought into position, the sleeve then being moved out to enclose said latter end.

The three piece sleeve of FIG. 5 includes side parts 17, 18 having flanges 17', 18' and a bottom part 19 which is wide enough to have its edges match the flanges, to which it may be bonded.

In each instance the bonding material is applied to the cleaned rail surfaces, the sleeve part or parts are positioned with clean inner surfaces facing the rail, and the entire sleeve is firmly pressed against the rail while the assembly is heated to ensure curing of the bonding material. It will be understood that the rail end surfaces are bonded as shown at 12 in FIG. 1, and the final result is a strongly "frozen" joint which cannot be accidentally loosened. Because of the greater surface area involved, the sleeves need not be as long as normal fish plates in order to give an equally strong bond.

It will be understood that various changes may be made in the form, construction, arrangement and materials of the joint structure and in the steps of the method without departing from the spirit and scope of the invention.

What I claim is:

1. A railroad rail joint comprising rail end portions and at least one additional metallic element having a surface complementary to at least a substantial proportion of the lateral surfaces of said rail end portions, said end portions and said element being substantially rigidly bonded together by the interposition throughout at least a major proportion of said complementary surfaces of a thermo-setting synthetic resin bonding agent.

2. A joint according to claim 1 in which the bonding agent is of approximately capillary thickness.

3. A joint according to claim 1 in which the rail end portions have butt end surfaces bonded together by the bonding agent as well as being bonded to said metallic element.

4. A joint according to claim 3 in which the connection between the butt ends of the rails includes at least

one shim interposed between the butt end surfaces and bonded thereto.

5. A railroad rail joint comprising rail end portions and fish plates substantially rigidly bonded together by the interposition throughout at least a major proportion of the fishing surfaces between said end portions and plates of a thermo-setting synthetic resin bonding agent.

6. A joint according to claim 5 which includes bolts so disposed as to hold the fish plates in close proximity to the rail end portions, parts of the surfaces of the bolts being bonded to the rail end portions and to the fish plates.

7. A railroad rail joint comprising rail end portions and a metallic sleeve element having an inner surface of extended area complementary to at least a substantial proportion of the lateral surfaces of said rail end portions, said complementary surfaces of the sleeve element and of the rail end portions being substantially rigidly bonded together by the interposition throughout at least a major proportion of said complementary surfaces of a thermo-setting synthetic resin bonding agent.

8. A joint according to claim 7 in which the rail end portions have butt end surfaces bonded together by the bonding agent as well as being bonded to said metallic sleeve element.

9. A joint according to claim 8 in which the connection between the butt ends of the rails includes at least one shim interposed between the butt end surfaces and bonded thereto.

10. A joint according to claim 1 in which the bonding agent consists predominantly of a reaction product of epichlorohydrin and p,p'-isopropylidene bisphenol.

11. A bolted frozen insulated rail joint comprising, in combination, a pair of rail ends, having bolt holes, a pair of joint bars having bolt holes, a settable bonding compound filling the space between the rail ends to form an end post, and a settable bonding compound in the space between the related load bearing faces of the rails and joint bars, bolts connecting the bars to the rails, said bonding compound joining the rail ends and bars and by-passing the strain on the bolts and end post directly from one rail to the other.
